TOBACCO CURING APPARATUS

James R. Henderson, Nashville, Ga.

Application August 29, 1939, Serial No. 292,486

8 Claims.

(Cl. 34—19)

This invention relates to tobacco curing devices and more particularly, to an improved means for supplying heat to a tobacco barn.

An object of this invention is to provide an improved means whereby heat may be discharged into the interior of a tobacco barn, the heat generating means being automatically controlled so that the temperature within the tobacco barn will not rise unduly or to the point where the tobacco will be liable to burn.

Another object of this invention is to provide an improved burner for generating heat together with an improved means for discharging heat about the lower portion of the barn so as to evenly distribute the heat within the barn.

A further object of this invention is to provide in a structure of this kind a plurality of heat outlets whereby the heat may be discharged in the barn and means connected to the outlets for automatically cutting off the discharge of heat in the barn when the temperature rises above a predetermined degree.

A still further object of this invention is to provide a heating flue which is extended interiorly of the tobacco barn and a plurality of valve members connected to the flue and adjustable relative thereto so that the heat in the flue may be discharged into predetermined parts of the barn.

A further object of this invention is to provide in a heating means of this type a hot air flue, a plurality of vertically adjustable valve members connected to the flue, a hood over each valve member and a damper for each valve member which is held in an open position by means of a cable or the like having a fusible element interposed therein so that in the event the temperature of the air in the barn rises to a predetermined degree, the fusible element will melt or break so as to thereby permit the dampers to automatically close and thus cut off the discharge of further heat within the barn.

A further object of this invention is to provide in a heating device of this kind a hot air flue which is positioned in the lower portion of the barn, means for generating heat in the flue, means for discharging the hot air from the flue into the barn and means for automatically cutting off the discharge of hot air into the barn, the latter means including means for automatically shutting off the source of heat in addition to opening the hot air flue to the atmosphere so that the hot air within the flue may readily pass out into the atmosphere and thus prevent burning of the tobacco within the barn.

To the above objects and to others which may

hereinafter appear, the invention consists of the novel construction, combination and arrangement of parts as will be more specifically referred to and illustrated in the accompanying drawings, wherein are shown embodiments of the invention, but it is to be understood that changes, modifications and variations may be resorted to which fall within the scope of the invention as claimed.

In the drawings:

Figure 1 is a horizontal section taken through a barn having a heating means constructed according to this invention mounted therein, the heating means being shown partly in top plan and partly diagrammatically.

Figure 2 is a detail top plan of the heating flue and hot air controlling means, a portion of the flue being broken away and in section.

Figure 3 is a detail side elevation of the heating device, the barn being broken away and in vertical section.

Figure 4 is a longitudinal section of the burner used with this invention.

Figure 5 is an enlarged fragmentary vertical section of one of the heat discharging elements.

Figure 6 is a fragmentary diagrammatical view of a modified form of this invention.

Figure 7 is a fragmentary top plan of a modified form of heat generating means.

Figure 8 is a detail side elevation of the structure shown in Figure 7, and

Figure 9 is a fragmentary side elevation of a further modification of heat generating means.

Referring to the drawings, the numeral 10 designates generally a tobacco barn within which tobacco is adapted to be suspended in the usual manner so that the tobacco leaves will be positioned above the floor or bottom of the barn. A heating flue 11 is disposed within the lower portion of the barn 10, one end of the flue 11 terminating exteriorly of the barn 10 and being open to the atmosphere. The inner end of the flue 11 is provided with a right angularly disposed branch 12 and a second branch 13 which extends rearwardly and in substantially parallel relation to the flue 11. The branch 13 is preferably disposed on an angle to the horizontal, rising above the intake end 14 of the flue 11. A branch 15 is connected to the forward end of the flue or branch 13 and an outlet pipe 16 is connected to the branch 15 and extends through the adjacent wall of the barn 10, being open at its outer end to the atmosphere.

A burner member generally designated as 17 is disposed within the intake end 14 of the flue 11

being provided with legs or base members 19 which engage the interior of the flue 11 so as to support the burner 17 substantially centrally of the intake end of the flue 11. As shown in Figure 2, the burner 17 is positioned inwardly of the intake end of the flue 11 and the burner 17 comprises a cylindrical body 19 having a rear end wall 20 provided with an air intake opening 21. The forward end of the cylindrical body 19 is provided with an inwardly curved flange 22 and a coil 23 is disposed in the forward end of the body 19. One end of the coil 23 has a fuel supply pipe 24 connected thereto and the opposite end of the coil 23 has a straight pipe 25 connected thereto 15 which extends through a partition 26 disposed within the body 19. A jet 27 is connected to the pipe 25 by a connecting pipe 28 so that the jet 27 will be in axial alignment with an opening 29 formed axially of the partition 26. The body 20 19 at a point rearwardly of the partition 26 is provided with an air vent or intake opening 30 which may be partly closed by means of a valve plate 31 slidably carried by guide members 32 secured to the outer side of the housing 19. By 25 providing the coil 23 forwardly of the jet 27 the fire from the jet 27 will pass through the coil 23 and thereby superheat the fuel flowing through the coil 23. In this manner, a lower grade of liquid fuel may be used than is the case 30 where the fuel jet is connected directly to the fuel supply line.

The fuel supply pipe 24 extends rearwardly and exteriorly of the burner 17 and is connected to a fuel supply line 33 by means of pipe connections 34, 35 and 36. A fuel valve 37 is interposed in the pipe 24 and is normally biased to a closed position by means of a spring 38. A check valve 39 is interposed in the pipe 24 adjacent the pipe coupling 35 and between this coupling 35 and the valve 37. This check valve is adapted to prevent 40 return flow of the fuel in the pipe 24. The main supply pipe line 33 is connected to a fuel reservoir or tank 40 and a main valve 41 is interposed in the main supply line 33. In practice, there may be two or more burners 17 connected to the main supply line 33 with each burner 17 being provided with an individual fuel valve 37. As shown in Figures 1 and 2, there are two flues 11 which are positioned in the lower portion of the barn 10. The fuel tank 40 is provided with an air line 42 connected to an air compressor 43 operated by means of an electric motor 44 or any other suitable source of power. The compressor 43 is adapted to maintain a predetermined amount of 45 air pressure in the reservoir 40 so that the fuel in the pipe line 33 and the line 34 will be under constant pressure. The motor 44 is automatically operated by means of a pressure member 45 which is interposed in the air line 42 and is connected to a switch structure 46 which is connected to one side 47 of a source of electric current supply 48. The other side 49 of the electric current supply is connected by means of a wire 50 to the motor 44. In this manner a constant air pressure is maintained within the fuel tank 40.

A plurality of upstanding nipples 51 are connected to the branches 12, 13 and 15 and a cylindrical valve member 52 engages in each nipple 51. The valve member 52 is provided at its lower end with a reduced portion 53 forming a baffle so as to direct hot air from the branch upwardly through the sleeve or valve member 52. The valve member 52 may be frictionally held in the nipple 51 although if desired any suitable holding

means may be provided so that the valve member 52 may be vertically adjusted relative to the nipple 51. In this manner the valve members 52 closest to the hot air flue 11 may have the lower ends thereof extended only a slight distance into the particular branch whereas succeeding valve members 52 may be extended to a greater degree downwardly into the branch or flue so as to thereby by-pass the hot air in the flue through the valve member 52.

Each valve member 52 has pivotally secured to the upper end thereof a damper plate 54 which is mounted on a hinge or pivotal structure 55. A bowed spring 56 is secured at one end to a valve member 52 and engages the damper 54 so as to bias the damper 54 to a closed position. A hood 57 of substantially conical configuration is disposed above the top of each valve member 52 and is supported above a valve member 52 by means of a pair of vertically disposed supporting arms or rods 58. These rods 58 have inwardly bent lower end portions 59 engaging outwardly offset arm supporting members 60 which may be struck from each nipple 51.

A damper 61 is mounted in the outlet end 16 of the hot air flue, the damper 61 being mounted on a shaft 62 which is journalled through the outlet member 16. One end of the shaft 62 is provided with a crank 63 and a spring 64 is connected at one end to the crank 63 and to the other end to a pin or stud 65 secured to the outlet member 16. The spring 64 is adapted to normally urge the damper 61 to an open position which is the position shown in dotted lines in Figure 2.

In order to provide a means whereby the dampers 54 may be held in open position, I have provided a flexible damper holding member 66 which is trained over pulleys 67, 68 and 69. The cable or damper holding member 66 engages through an eye or guide member 70 carried by each damper 54 and the pulleys 68 and 69 are supported in a position whereby the cable 66 will be disposed immediately above the valve members 52. The pulleys 68 and 69 are supported by means of supporting brackets 71 and 72 which are secured to the barn 10. As shown in Figure 2, the flexible member 66 extends from the pulley 67 above the branch 15, longitudinally of the flue 13 above the branch 12 and then crosses over to the second heating means where the cable 66 is extended over the flue in the same manner as over the first flue.

A fusible element 73 is interposed in the cable 66 between the two flue members 11 and is positioned at the end of the barn 10 opposite from the intake end of the flue members 11. The fusible element 73 is adapted to normally hold the cable 66 taut but when the temperature of the air in the barn 10 rises to a predetermined degree, the fusible element 73 is adapted to melt so as to separate the adjacent ends of the cable 66 and thus permit the cable 66 to slacken. When the cable 66 becomes slack the valve members 54 will be swung downwardly to a closed position by the valve closing springs 56.

The opposite ends of the cable 66 are extended rearwardly as at 74 and connected to an arm 75 carried by each valve member 52. The cable 74 is supported by means of a supporting member 76 and a pulley 77 is secured to the upper end of the supporting member 76. By connecting each valve member 52 with the damper opening cable 66 when the fusible member 73 breaks the cable 66, the fuel valves 37 will be closed by the 75

valve closing springs 38 and thus cut off the supply of fuel to each burner 17.

A cable 78 is connected at one end to the cable 66 and at the opposite end to a crank 19 carried by each damper shaft 62 opposite from the crank 63. The cable 78 is adapted when the cable 66 is taut to hold the damper 61 in a substantially closed position. In this manner the hot air in the flue 11 will not be permitted to discharge 10 into the atmosphere when the dampers 54 are open.

In Figure 6, there is shown a modified arrangement of the heating flues wherein the intake flue 11^a is connected to the bight 80 of a U-shaped 15 flue member 81. The parallel sides 82 of the flue 81 extend rearwardly from the bight or branch 80. The branch 80 may be provided with baffles 83 so as to direct the hot air from the flue 11^a to the opposite ends of the branch 80 and into 20 the parallel sides 82 thereof. A cable 66^a similar to the cable 66 is supported above the hot air flue 81 by supporting members 12^a and a fusible element 73^a is interposed in the cable 66^a. The remaining structure associated with the hot air flue 11^a is similar to the structure shown with respect to the flue 11 and the outlet 16.

In the use and operation of this heating means the main valve 41 is open so as to permit the fuel under pressure from the reservoir 40 to flow to 30 the burners 17. The hot air valve members 52 are vertically adjusted so as to by-pass the hot air from the flue 11 and the flue members 12, 13 and 15 upwardly into the interior of the barn. The dampers 54 will be maintained in an open 35 position so long as the damper holding cable 66 is held taut by the fusible element 73. The damper 61 will be maintained in a closed position when the burner 17 is in operation so that the hot air in the flues will be discharged into the 40 interior of the barn 10. Where coal, wood or other fuel is used in place of the burner 11 the normal position of the damper 61 may be reversed so that this damper 61 will be normally 45 open and thus permit the smoke to pass out of the flues.

In the event the air in the barn 10 becomes too hot, the fusible element 73 will melt or part thereby permitting the cable 66 to slacken. When the cable 66 becomes slack, the spring 56 for the 50 dampers 54 will close the dampers 54 so as to cut off further discharge of the hot air from the flues into the interior of the barn. At the same time that the dampers 54 are closed by the springs 56, the fuel valve 37 will be moved to a closed position by the spring 38 and the spring 64 will simultaneously swing the damper 61 to an open position. With the damper 61 in an open position, the excessive hot air in the flues will be promptly discharged into the atmosphere exteriorly of 55 the barn 10. In this manner the fusible element 73 will not permit the temperature of the air in the barn 10 to rise above a predetermined degree, which degree is the temperature at which the fusible element 73 will melt or part.

A heating means constructed according to this 60 invention will provide the desired amount of dry smokeless hot air within the barn so as to thoroughly and quickly dry the tobacco without subjecting the tobacco to a scorching heat which 65 might cause the tobacco to burn, and which might at the same time cause it to sponge or discolor.

The quality of fuel used for the burner 17 may be kerosene, furnace oil or any other suitable combustible fuel. By providing the heating coil 70

23 in the burner 17 the grade of this combustible fuel may be relatively low as the fuel flowing to the jet 27 is heated to a point where it will readily vaporize when the fuel is discharged from the jet 27.

In Figures 7 and 8 there is disclosed a slightly modified form of this invention, wherein a burner 17^a similar to the burner 17 is mounted in a pipe or tube 84 which is open at its outer end and which at its inner end is provided with a U-shaped portion 85. The two arms of the U-shaped portion 85 are adapted to be connected to a pair of hot air flues 11^a similar to the flues 11 so that a single burner 17^a may be used for heating a pair of hot air flues.

As shown in Figure 8 the outer end of the pipe 84 is reduced as at 86 and the pipe 84 increases in diameter forwardly of the burner 17^a. An upwardly extending nipple 87 is carried by the pipe 84 above the burner 17^a and forwardly thereof. A damper 88 is mounted in the nipple 87 and is adapted to control the amount of air which is admitted to the pipe 84 forwardly of the burner 17 in order to facilitate the combustion of the fuel.

In Figure 9 there is disclosed a structure somewhat similar to that shown in Figures 7 and 8 wherein a pipe 84^b is provided similar to the pipe or tube 84 having a reduced forward or outer end portion 86^b within which a burner 17^b is positioned. The pipe 84 forwardly of the burner 17^b increases in size as at 88 and an upstanding nipple 87^b is carried by the pipe 84^b forwardly of the burner 17^b. A damper 88^b is carried by the nipple 87 in order to admit a predetermined quantity of air into the pipe 84^b forwardly of the burner 17^b. The inner end of the pipe 84^b is adapted to be connected to a hot air flue 11^b, the construction of the flue 11^b being similar to the flue 11 and the remaining structure shown in Figures 1 and 2.

What I claim is:

1. A tobacco barn heater comprising a flue adapted to be positioned within the lower portion of the barn, a heating means in said flue at one end thereof, a plurality of upstanding nipples carried by and communicating with said flue, and a cylindrical body slidably mounted in a nipple, said body including a part adapted to be projected interiorly of said flue to thereby by-pass 60 hot air from said flue through said body.

2. A tobacco barn heater comprising a flue adapted to be positioned within the lower portion of the barn, a heating means in said flue at one end thereof, a plurality of upstanding nipples 55 carried by and communicating with said flue, a cylindrical body slidably mounted in a nipple, said body including a part adapted to be projected interiorly of said flue to thereby by-pass hot air from said flue through said body, a hood disposed above said body, and means engaging a hood and supported from a nipple for supporting the hood above the body in the nipple.

3. A tobacco barn heater comprising a flue adapted to be positioned within the lower portion of the barn, a heating means in said flue at one end thereof, a plurality of upstanding nipples carried by and communicating with said flue, a cylindrical body supported in a nipple, said body including a part adapted to be projected interiorly of said flue to thereby by-pass hot air from said flue through said body, a hood disposed above said body, means engaging a hood and supported from a nipple for supporting the hood above the body in the nipple, a damper pivotally 70

75

carried by each body at the upper end thereof, means normally biasing said damper to a closed position, and temperature controlled means for holding said dampers in open position.

5. A tobacco barn heater comprising a flue adapted to be positioned within a barn, a heating means in said flue at one end thereof, a plurality of upstanding nipples carried by and communicating with said flue, a cylindrical by-pass body 10 in each nipple and including a part projecting into said flue to by-pass a predetermined amount of hot air through said body, a closure for each body, means hingedly securing said closure to a body, a spring constantly urging said closure to a closed position, a flexible member engaging each closure for holding said closures in open position, and fusible means connected to said flexible member for normally holding said flexible member taut.

20. 5. A tobacco barn heater comprising a flue adapted to be positioned within a barn, a heating means in said flue at one end thereof, a plurality of upstanding nipples carried by and communicating with said flue, a cylindrical by-pass body 25 in each nipple and including a part projecting into said flue to by-pass a predetermined amount of hot air through said body, a closure for each body, means hingedly securing said closure to a body, a spring constantly urging said closure to a closed position, a flexible member engaging each closure for holding said closures in open position, fusible means connected to said flexible member for normally holding said flexible member taut, a damper in the opposite end of said flue, means 30 constantly urging said damper to an open position, and means connecting said damper with said flexible member to thereby hold said damper closed when said flexible member is taut.

40. 6. A tobacco barn heater comprising a flue adapted to be positioned within a barn, a liquid fuel burner in one end of said flue, a pipe connecting said burner with a source of fuel supply, a valve in said pipe, spring means normally urging said valve to closed position, a plurality of nipples 45 carried by said flue, a by-pass member adjustably engaging each nipple, a closure for each by-pass member, means constantly urging said clo-

sures to closed position, an eye carried by each closure, a flexible member engaging through said eyes, means connecting one end of said flexible member to said valve, and a fusible element connected to the opposite end of said flexible member and normally holding said flexible member taut to thereby hold said valve in open position and simultaneously hold said closures open.

5. A tobacco barn heater comprising a flue adapted to be positioned within a barn, a liquid fuel burner in one end of said flue, a pipe connecting said burner with a source of fuel supply, a valve in said pipe, spring means normally urging said valve to closed position, a plurality of nipples carried by said flue, a by-pass member 10 adjustably engaging each nipple, a closure for each by-pass member, means constantly urging said closures to closed positions, an eye carried by each closure, a flexible member engaging through 15 said eyes, means connecting one end of said flexible member to said valve, a fusible element connected to the opposite end of said flexible member and normally holding said flexible member taut to thereby hold said valve in open position and simultaneously hold said closures open, a 20 damper in the opposite end of said flue, a spring constantly urging said damper to open position, and means connected to said damper and to said flexible member for holding said damper closed when said flexible member is taut.

25. 8. A tobacco barn heater comprising a pair of flue members adapted to be positioned within the lower portion of the barn, a plurality of upstanding nipples carried by and communicating with said flues, a cylindrical body supported in each nipple, said body including a part adapted to be disposed interiorly of a flue to thereby by-pass hot air from said flue through said body, a closure pivotally carried by each body, fusible means connected to said closures for holding said 30 closures in open position, yieldable means constantly urging said closures to closed position, a burner, a pipe about said burner, a U-shaped pipe connected to said first pipe and to said pair of flues, a nipple carried by said first pipe, and a 35 damper engaging said latter nipple.

JAMES R. HENDERSON.
